UNITED STATES PATENT OFFICE.

WILLIAM H. REDHEFFER, JR., OF PHILADELPHIA, PENNSYLVANIA, ASSIGNOR
OF TWO-THIRDS TO ROBERT RODGERS AND FRANK BRIGGS, OF SAME
PLACE.

DESIGN FOR A GAME-BOARD.

SPECIFICATION forming part of Design No. 25,900, dated August 4, 1896.

Application filed July 3, 1896. Serial No. 598,042. Term of patent 7 years.

To all whom it may concern:

Be it known that I, WILLIAM H. REDHEFFER, Jr., a citizen of the United States, and a resident of the city of Philadelphia, State 5 of Pennsylvania, have invented a certain new Design for Game-Boards, of which the following is a full, clear, and exact description, reference being had to the accompanying drawings, forming part of the specification.

10 My design for game-boards is fully illustrated in the accompanying drawings, in which—

Figure 1 is a perspective view of the game-board; and Fig. 2 is a transverse sectional 15 elevation of the same on the line 2 2, Fig. 1.

The board comprises a base A, substantially rectangular in form and surrounded by vertical walls A'. The base A is flat, and on its upper surface are provided a number of circular concaved depressions arranged substantially in the manner illustrated, a row of concaved depressions $a a' a^2 a^3 a^4 a^5$ extending in a straight line between diagonally opposite corners of the base, the three concaved depressions $a a' a^2$ being somewhat closer together 20 and nearer one corner of the board than the remaining depressions in this row. The re-

maining three are disposed at substantially equal distances in the line. Extending at right angles to the first row of depressions 30 are two smaller rows of circular depressions of three each, the depression a^3 forming the center of a row comprising two other depressions $b b'$, and the depression a^4 forming the center of a row in which are two other concaved depressions $c c'$, and arranged centrally within a space bounded by the depressions a^3, a^4, c , and b is a concaved depression d . Surrounding the depressions a^3, a^4, b and b' are marked small squares e , which squares 40 are connected in such manner as to form an enlarged square space by lines $f f' f^2 f^3$.

Having thus described my invention, what I claim, and desire to secure by Letters Patent, is—

45 The design for a game-board substantially as illustrated and described.

In witness whereof I have hereunto set my hand this 2d day of July, A. D. 1896.

WILLIAM H. REDHEFFER, JR.
